LOOSE-LEAF BINDER.

1,391,079.

Specification of Letters Patent. Patented Sept. 20, 1921.

Application filed June 7, 1920. Serial No. 387,022.

To all whom it may concern:

Be it known that I, ADOLPH RUBIN, a citizen of the United States, residing at St. Louis, Missouri, have invented a certain new and useful Improvement in Loose-Leaf Binders, of which the following is a full, clear, and exact description, such as will enable others skilled in the art to which it appertains to make and use the same.

10 This invention relates to loose leaf binders of the type in which the leaves are retained in position by tapes, bands or cords connected to a winding shaft which can be turned in one direction to tighten the tapes, 15 and thus cause the leaves to be securely clamped between portions of the binder.

Many of the loose leaf binders of the particular type referred to that are now in general use are provided with a winding shaft 20 which is journaled in a supporting member that extends the entire length of the binder, said supporting member usually having a number of bearings for the winding shaft, and slots up through which the tapes lead 25 from the underside of the winding shaft.

Accordingly, a great number of different sizes of winding shaft supporting members have to be kept in stock to supply the demand for binders of varying lengths and 30 binders that are equipped with two, three, four or more tapes, as it is not possible to use the same shaft supporting member for a long binder and for a short binder, or for a two, three or four tape binder.

35 One of the objects of my present invention is to provide a loose-leaf binder that is composed of standard parts or units which can be used with long or short books or books whose leaves are held in place with two, 40 three, four or more tapes.

Another object is to provide an inexpensive loose leaf binder of substantial construction whose winding shaft is normally locked by a mechanism of novel design that 45 cannot be released or rendered inoperative by an unauthorized person.

Another object is to provide a key-operated loose leaf binder which is so constructed that a simple rotary movement of 50 the winding key in one direction releases the winding shaft and turns it in a direction to slacken the tapes and rotary movement of said winding key in the opposite direction tightens the tapes, the binder being equipped

with a ratchet mechanism that makes a noise 55 when the winding shaft is being turned in one direction and which remains silent when said shaft is being turned in the opposite direction, thereby enabling the user to easily determine whether the winding shaft is being turned in a direction to slacken or tighten the tapes. Other objects and desirable features of my invention will be hereinafter pointed out.

Figure 1 of the drawings is a top plan 65 view of a loose leaf binder constructed in accordance with my invention with the leaves of the book omitted so as to more clearly show the construction of the binder.

Fig. 2 is a transverse sectional view, taken 70 on the line 2—2 of Fig. 1, looking in the direction indicated by the arrow, showing the leaves of the book clamped together by the 75 tapes of the binder.

Fig. 3 is a perspective view of the stationary element of the ratchet locking mechanism for the winding shaft; and

Fig. 4 is a detail sectional view of a portion of the winding key and the tapered collar on the winding shaft.

Referring to the drawings which illustrate the preferred form of my invention, A designates the winding shaft of my improved binder, and B designates tapes or bands of flexible material that pass through 85 slots in leaves C which are arranged between the covers D of the binder, said tapes being connected at one end to a leaf clamping member E carried by one of the covers D of the binder and combined with leaf clamping 90 members carried by the other cover of the binder in such a manner that when the winding shaft A is turned in one direction the tapes will be tightened so as to draw the leaf clamping members together and thus 95 securely clamp the leaves C of the binder between said members.

Instead of mounting the winding shaft A in bearings on a part, usually a leaf clamping member, that extends the entire length 100 of the binder, as has heretofore been the usual practice in one type of loose leaf binder that is now in general use, I mount the winding shaft of my improved binder in a plurality of members, each of which 105 consists of a separate unit that is detachably connected to one of the covers of the binder. One of said units carries all of the elements

of the locking mechanism for the winding shaft and the other units each consist of a part that assists in supporting the winding shaft and which forms a portion of a leaf 5 clamping element on one of the covers of the binder. Said elements can be arranged closely together or far apart so as to vary the distance between the tapes of the binder and two, three, four or more of said elements 10 can be used in a binder, depending upon the number of tapes the binder is equipped with. In other words, my improved binder may be said to comprise a main section or unit that forms the principal support for the winding shaft and which carries the locking mechanism for said winding shaft and one or more additional sections or units adapted to be arranged in various positions with relation to the main 15 element, depending upon the spacing desired between the tapes, or the number of tapes the binder is to be equipped with.

In the binder herein shown, which is equipped with two tapes B, the winding 20 shaft A is journaled in a main section or unit F arranged at the lower end of the binder and an auxiliary section or unit F' arranged at the upper end of the binder. If it is desired to construct a three tape binder, 25 one unit F and two auxiliary units F' are used. The units F and F' are detachably connected to one of the covers of the binder, thereby enabling them to be arranged comparatively closely together or spaced far 30 apart. The unit F comprises a leaf clamping portion 1 provided with a plurality of bearings 2 in which the winding shaft A is journaled and having a slot 3 up through which the lower tape B leads from the underside of the winding shaft, said tape extending transversely through the leaves C of the binder and having its opposite end connected in any preferred manner to the leaf clamping member E carried by the other 35 cover of the binder, as shown more clearly in Fig. 2. The auxiliary element F' also comprises a leaf clamping portion 1' provided with a plurality of bearings 2' for the winding shaft and having a slot 3' up through 40 which the upper tape B leads from the underside of the winding shaft, as shown in Fig. 1.

The units F and F' can be detachably connected to one of the covers D of the 45 binder in various ways without departing from the spirit of my invention, but I prefer to connect said elements to the left hand cover by a flexible hinge 4 provided with a rod or piece of wire 5 so as to form a reinforced edge to which the elements F and F' can be secured, preferably by crimping or bending portions 6 and 6' of said units over the reinforced edge of said flexible hinge. The leaf clamping member E that is carried 50 by the right hand cover D of the binder

is preferably connected to same by a flexible hinge 4'. The locking mechanism for the winding shaft is so constructed that an unauthorized person cannot turn the winding shaft in a direction to slacken the tapes B 55 sufficiently to permit the leaves C to be removed. Said locking mechanism is composed of a ratchet wheel 7 of tubular form mounted on the winding shaft A, a cooperating stationary ratchet element 8 of tubular form through which the winding shaft passes and a coiled spring 9 mounted on the winding shaft between the ratchet wheel 7 and one of the bearings 2 on the unit F for exerting pressure on said ratchet wheel 7 60 in a direction tending to hold it in engagement with the stationary ratchet element 8. The means for disengaging the ratchet wheel 7 from the stationary ratchet element 8 consists of a rod 10 arranged in a longitudinally-disposed groove in the winding shaft A and provided at its upper end with a lateral extension 10' that fits in an elongated slot 7' in the ratchet wheel 7, a collar 11 65 slidably mounted on the winding shaft and rigidly connected to the lower end of the rod 10, as for example, by means of a pin or a lateral extension 11' on said rod, and a key G that is adapted to be slipped over the lower end of the winding shaft and which is so constructed that rotary movement of said key in anti-clockwise direction exerts upward pressure on the collar 11, so as to disengage the ratchet wheel 7 from the stationary element 8 of the ratchet mechanism, and thus permit the winding shaft to be turned in a direction to slacken the tapes B. When said key G is turned in the reverse direction the winding shaft A 70 will be rotated in a direction to tighten the tapes. As shown in Fig. 1, the key G is provided with a tubular portion 12 having an inclined slot 13 open at one end and adapted to receive a laterally-projecting pin 14 on the winding shaft A. The lower end 75 of the collar 11 is preferably tapered to a knife edge, as shown in Fig. 4, so as to eliminate a shoulder on said collar against which an instrument other than the key G can be placed, so as to force the collar upwardly. The end of the key G is so shaped that it will conform to the tapered end of the collar 11. When the key G is slipped over the lower end of the winding shaft and turned to the left or in anti-clockwise direction, 80 said key will be moved upwardly (looking at Fig. 1) by the engagement of the walls of the inclined slot 13 in the tubular portion of said key with the pin 14 on the winding shaft, thereby causing the collar 11 to move upwardly sufficiently to cause the rod 10 to disengage the ratchet wheel 7 from the stationary element 8 of the ratchet mechanism. Continued rotary movement of the key G to the left causes the winding 85

120

125

130

shaft to turn in a direction to slacken the tapes B. When the winding key G is turned in the opposite direction, a shoulder or straight portion 13^a of the slot 13 in the tubular portion of the key bears against the pin 14 on the winding shaft and causes the winding shaft to rotate in a direction to tighten the tapes, the first portion of the rotary movement of the winding key to the right 10 or in clockwise direction permitting the spring 9 to move the ratchet wheel 7 downwardly into engagement with the stationary element of the ratchet mechanism. Accordingly, when the winding shaft is being turned in a direction to tighten the tapes, the ratchet wheel 7 will snap over the stationary element 8 of the ratchet mechanism and make a noise, thus notifying the user that the winding shaft is being turned in 15 the proper direction. When the winding shaft is being turned in the opposite direction, namely, to slacken the tapes, the ratchet mechanism is silent, due, of course, to the fact that the ratchet wheel 7 is then held 20 out of engagement with the stationary element 8 of the ratchet mechanism. In the binder herein shown the stationary element 8 of the ratchet mechanism is connected to the unit F of which it forms a part by means 25 of a bifurcated portion 15 on said element 8 that fits in a notch 16 in the portion of the unit F that carries the shaft bearings 2, but it will, of course, be understood that it is immaterial, so far as my broad idea is 30 concerned, how the stationary element 8 of the ratchet mechanism is retained in position.

By constructing the binder in the manner above described, namely, using a main unit 35 that carries the locking mechanism for the winding shaft and forms the main support for the winding shaft and one or more auxiliary units that can be slipped over the winding shaft and arranged in any desired 40 position with relation to the main unit, I overcome the necessity of carrying in stock parts that are suitable only for a binder of a particular length or for a binder provided with a certain number of tapes. Moreover, 45 such a binder is inexpensive to manufacture; it is provided with a locking mechanism for the winding shaft that is not liable to break or get out of order when in service, and said locking mechanism is of such de- 50 sign that it can not be released or rendered inoperative by a clock key or similar socketed key. Such a binder is easy to operate, due to the fact that a simple twist of the winding key to the left releases the winding 55 shaft, and further rotary movement of the winding key to the left causes the winding shaft to turn in a direction to slacken the tapes, the ratchet mechanism of the winding shaft being silent when the winding shaft 60 is being turned in a direction to slacken the 65

tapes and making a noise when said shaft is being turned in a direction to tighten the tapes, thus enabling the user to determine whether the winding shaft is being turned in the proper direction.

Having thus described my invention, what I claim as new and desire to secure by Letters Patent, is:

1. A loose leaf binder provided with a winding shaft, a plurality of flexible leaf 75 retaining members spaced apart and adapted to be connected to said shaft, and a plurality of separate and distinct supporting members for said winding shaft capable of being arranged in various positions so as 80 to vary the spacing between said leaf retaining members.

2. A loose leaf binder, comprising a winding shaft, a plurality of tapes, a locking mechanism for said winding shaft, a main 85 unit that supports said winding shaft and locking mechanism, and an auxiliary support for said shaft formed by an additional unit that is separate and distinct from said main unit.

3. A loose leaf binder, comprising a winding shaft, a plurality of flexible leaf retaining elements, and a plurality of separate and distinct members, each of which serves 90 as a support for the winding shaft and having a guide for one of the leaf retaining elements of the binder.

4. A loose leaf binder, comprising a plurality of separate and distinct leaf clamping members arranged in spaced relation, a tape 100 associated with each of said leaf clamping members, and a winding shaft for operating all of said tapes.

5. A loose leaf binder, comprising a winding shaft, covers, a plurality of tapes, and 105 a plurality of bearings for said winding shaft detachably connected to one of said covers and arranged in spaced relation and each provided with a guide for one of the tapes of the binder.

6. A loose leaf binder, comprising a winding shaft, a plurality of tapes, a locking mechanism for said winding shaft, a main 115 unit for carrying said locking mechanism and provided with a guide for one of the tapes, and an auxiliary unit or units associated with the other tape or tapes and arranged in spaced relation with said main unit, said main unit and auxiliary unit or units having bearings for the winding shaft. 120

7. A loose leaf binder provided with a winding shaft, a tape connected to said shaft, a locking mechanism for said shaft comprising two coöperating ratchet elements through which the shaft passes, one of said elements being mounted in such a manner that it can move longitudinally of the shaft, a winding key that is adapted to be mounted on the winding shaft, and means whereby rotary movement of said key in one direc- 125 130

tion causes said ratchet elements to be disengaged and the winding shaft to thereafter turn with said key.

8. A loose leaf binder provided with a winding shaft, a tape connected to said shaft, a locking mechanism for said shaft comprising a stationary ratchet element, a coöperating movable ratchet element mounted on the winding shaft in such a manner that it can move longitudinally of said shaft but cannot turn with relation to the shaft, a winding key that is adapted to be mounted on one end of the winding shaft, and means whereby a slight rotary movement of said key in one direction with relation to said shaft causes said ratchet elements to be disengaged.

9. A loose leaf binder provided with a winding shaft, a leaf retaining element connected to said shaft, a locking mechanism for said shaft, comprising a ratchet wheel mounted on said shaft in such a manner that it can move longitudinally of same but not turn with relation to the shaft, a sliding collar on said shaft connected with said ratchet wheel, a winding key adapted to be mounted on said shaft, and means whereby a slight rotary movement of said key in one direction causes said collar to be shifted in a direction to disengage said ratchet wheel from the part with which it coöperates.

10. A loose leaf binder provided with a winding shaft, a tape connected to said shaft, a locking mechanism for said shaft comprising coöperating ratchet elements of substantially tubular form through which the shaft passes, said elements being arranged some distance from the end of the shaft, and means on said shaft adapted to be engaged by a key for causing one of said ratchet elements to move out of engagement with the other and thus release the shaft.

11. A loose leaf binder provided with a winding shaft, a tape connected to said shaft, a locking mechanism for said shaft comprising a stationary ratchet element through which the shaft passes, a ratchet wheel on said shaft mounted in such a manner that it can move longitudinally of the shaft, a rod arranged in a groove in said shaft and connected to said ratchet wheel mounted on the shaft, a sliding collar on said shaft connected to said rod, a stationary abutment on said shaft, and a key having a portion that is adapted to be inserted between said abutment and collar so as to disengage said

ratchet wheel from the stationary element of the ratchet mechanism.

12. A loose leaf binder, comprising a winding shaft, a member in which said shaft is journaled, a stationary ratchet element on said member through which the winding shaft passes, a coöperating ratchet wheel on said winding shaft, a spring for holding said ratchet wheel in engagement with said stationary element, a rod arranged in a longitudinally-disposed groove in said winding shaft and provided with an extension that projects into an elongated slot in said ratchet wheel, a sliding collar on said shaft connected to said rod, and a rigid abutment or pin on said shaft that is adapted to coöperate with a device used to move said collar longitudinally of the winding shaft so as to disengage said ratchet wheel from the element with which it coöperates.

13. A loose leaf binder, comprising a winding shaft, a member having bearings through which said shaft passes, a substantially tubular-shaped ratchet element surrounding said winding shaft and having a bifurcated portion that fits in a notch in said shaft supporting member, a spring-pressed ratchet wheel arranged on said shaft in engagement with said ratchet element, a collar slidably mounted on said shaft adjacent the outer end of same and connected with said ratchet wheel, and means for moving said collar longitudinally of said shaft so as to disengage said ratchet wheel from its coöperating element.

14. A loose leaf binder, comprising a winding shaft, a plurality of tapes, a plurality of units, each of which has a bearing for said shaft and a guide through which one of said tapes passes, and a locking mechanism for said shaft associated with one of said units and comprising coöperating ratchet elements and means that is adapted to be operated by a winding key for disengaging said elements so as to release the winding shaft.

15. A loose leaf binder, comprising covers, a hinge connected to one of said covers and provided with a reinforced edge, a winding shaft, a plurality of leaf retaining elements, and a plurality of separate and distinct supporting members for said winding shaft having portions that are crimped or pressed onto the reinforced edge of said hinge.

ADOLPH RUBIN.
